COMBINED TYPEWRITING AND COMPUTING MACHINE

Henry L. Pitman, Hartford, Conn., assignor to
Underwood Corporation, a corporation of Delaware

Application June 30, 1942, Serial No. 449,049

13 Claims. (CL 235—60)

This invention relates to combined typewriting and computing machines of the kind exemplified in my Patent No. 2,192,365, dated March 5, 1940. In its more particular aspects, the invention relates to type-action and case-shift mechanism and operation thereof under control of a totalizer and a typing carriage to print positive totals and overdraft totals automatically.

In such machines, the amount-typing operations of numeral type-actions index the amount by setting digit pins in denominational orders which are selected by seriatim operation of denominational jacks by the carriage. Following the indexing, the machine is cycled and mechanism is thereby operated, according to the values of the set digit pins, to enter the amount in a totalizer comprising a set of accumulating wheels.

For a total printing, numeral agents and an extra case-shift agent, the agents being in the form of a set or nest of transverse blades, are selectable under control of a machine-reading of a total in the accumulating wheels. The selected blades are operable seriatim in denominational order to cause connection of corresponding numeral type-actions and, possibly, a case-shift action to a power-drive for operation by the latter. The seriatim operation of the blades is effected through seriatim operation of the aforesaid denominational jacks as the carriage letter-feeds at operation of the type-actions.

Heretofore, the operation of the blades by the denominational jacks has been translated by mechanical connections into connection of the type-actions and case-shift-action to the power-drive, as exemplified in my aforesaid patent.

Owing to the small extent of a letter-space step, usually one-tenth of an inch, the carriage, in one step, can scarcely release a jack and a thereby operated blade and permit these to become restored before depressing the next jack and operating its blade. Hence, it has been difficult, with the aforesaid mechanical connections operated by the blades at operation of the jacks, to obtain such distinctly seriatim operation of the type-actions as will conduce to avoiding interferences of parts and other disadvantages which arise as where any one type-action operation overlaps the next or previous one.

An object of the invention is to provide improvements whereby these difficulties are overcome. In carrying this out, there may be retained the aforesaid blades, the means for selecting them under total-reading control of the accumulating wheels, and the means for operat-

ing the selected blades through the carriage-operated denominational jacks, and the improvements may be made in means whereby operation of the blades results in properly timed connection of the type-actions or case-shift action to the power-drive. Preferably, in carrying this out, electromagnet means are employed and operate under control of the blades to connect the type-action or case-shift action to the power-drive, and proper timing is obtainable by carriage control of the time or instant of energization of the magnet.

A further object is to provide an improved type-action system that is simple, inexpensive, reliable in operation, and consists of few parts that take up little room so that the typing mechanism is open and accessible for inspection and servicing, and leaves room for the installation of contact devices for the offset electromagnet means.

A feature of the improved type-action system is in provision for conditioning the "0" and the "9" type-actions so that either of these is operable in part, that is, without printing, for indexing and for advancing the carriage automatically from a starting or highest denominational position to the position where the first significant figure of a positive total or overdraft total is to be printed. The "0" type action is partly usable for this purpose in the case of a positive total where the highest accumulating wheel and one or more lower wheels may register insignificant zeros. Similarly, in the case of an overdraft total, the "9" type-action may be partly used in correspondence to those wheels that register insignificant nines.

Other features of the invention relate to restoring the "0" and "9" type-action in response to the operation of a type-action for the first significant figure of a total so that a "0" or "9" may be typed after the first significant figure.

In the case of an overdraft, the accumulating wheels register the complement of the true overdraft and the type-actions are selected according to the complement. The type-actions, however, have upper-case numeral types which are the complements of their lower-case types; and if the wheels register an overdraft, the aforesaid case-shift blade is automatically caused initially to be operated to effect the case shift preparatory to actually typing the true overdraft. The operation of the case-shift mechanism under control of the case-shift blade causes the "9" type-action to be conditioned for partial operation, that is, operation without printing, and then to be op-

erated to index "9" and letter feed the carriage. This result of a case-shift operation, however, must not occur if the case-shift mechanism is operated aside from total printing and merely for upper-case typing, and the invention, therefore, provides a case-shift mechanism organized to meet these conditions.

Other objects, features, and advantages will hereinafter appear.

In the drawings:

Figure 1 is a cross sectional side elevation of a combined typewriting and computing machine embodying the invention;

Figure 2 is a front elevation of parts of the type-action system and case-shift action;

Figure 3 is a perspective of the "0" type action and associated mechanism and includes a showing of part of another numeral type-action;

Figure 4 is a perspective of the "9" type action, the escapement mechanism, and part of the case-shift type-action;

Figure 5 is a side elevation, partly in section, of parts of the case-shift mechanism;

Figure 6 is a side elevation, partly in section, of the "9" type action, the case shift action, and associate mechanisms;

Figure 7 is a front elevation of parts of the case-shift mechanism;

Figure 8 is a rear view perspective of the escapement mechanism and its operative connections to a circuit controlling switch;

Figure 9 is a rear view perspective of the escapement and switch in operated positions;

Figure 10 is a circuit diagram;

Figure 11 is a perspective of the contact mechanism with parts shown broken away and sectioned to bring out details;

Figure 12 is a partly sectioned rear elevation of the magnets and mounting structure; and

Figure 13 is a front elevation of the contact mechanism.

A typewriter T surmounts a computing base B, Fig. 1. A work-sheet platen 20 is journaled in a carriage C movable upon front and rear carriage rails 22, 23 supported by the typewriter frame F.

Type actions

Type bars 24 are operable to print at a common printing point and are pivoted at 25 in a type bar segment 26 which may be case-shiftable, as later described, each type bar having lower and upper case types 27. A cross member 30 supported within frame F has a series of slots 31 and a transverse fulcrum rod 32. A bank of numeral keys 33 and other banks of alphabet and character keys 34 are on key levers 35 received in corresponding slots 31 of member 30 and fulcrumed on rod 32. Associated with each key lever 35, and also fulcrumed on said rod 32, there is a sub-lever 36 which may be received in the same slot 31 with said key lever. Each sub-lever 36 for a numeral type-action has a downwardly extending operating arm 37, a forwardly extending pin setting arm 38, and an upwardly extending type-bar actuating arm 39. The sub-lever 36 for any other than a numeral type-action need not have the pin setting arm 38, but will have the arms 37, 39, as represented by the first sub-lever 36 from the left in Fig. 3. The horizontal spread of the system of key levers 35 and sub-levers 36 is more than the spread of the arcuate system of type bars 24. As represented at Fig. 2, showing only the right half portions of the system, the

left half portions being similar, the upstanding arms 39 of sub-levers 36 are at graded lengths from the sub-lever fulcrum 32, and the upper portions of said arms 39 are made to converge, as by graded bends 40, so that the upper ends of said arms 39 have substantially the same arcuate array as arms 41 of the type bars 24, each type bar arm 41 being connected to its sub-lever by a link 42. At the case shifts of the type bar system, the links 42 may swing freely at their points of attachment to the sub-levers 36 and type bar arms 41.

The operating arm 37 of each sub-lever 36 has pivoted thereto at 43 a draw link 44 to which is pivoted a toothed dog 46. The draw links 44 have substantially uniform extents of type-action driving movements, and the type bar links 42 also have uniform extents of movements. The lengths of the sub-lever arms 37 from fulcrum 32 to the draw link pivots 43 vary, Fig. 2, in proportion to the lengths of the sub-lever arms 39 from fulcrum 32 to links 42. A fluted universal snatch roll 47 is journaled within the typewriter frame F. A power drive, not shown, rotates snatch roll 47 counterclockwise, Fig. 1, continuously. When a draw link 44 is lifted and its dog 46 engaged with snatch roll 47, the latter initially rotates said dog clockwise to a stop 49 on the draw link and then the draw link is driven rearwardly to turn its sub-lever 36 counterclockwise about fulcrum 32 to swing its type bar 24 toward the platen 20 in a printing stroke. A cam edge 50, Fig. 6, of the draw link 44 encounters a knock-off screw 51 so that the draw link becomes disengaged from snatch roll 47 at a suitable instant before the type bar strikes the platen, the printing stroke being completed by momentum of the type action. A bar 48, supported in the framework, presents a knock-off screw 51 for each type-action. A downwardly and forwardly pulling spring 52, attached to the draw link 44, returns the type-action to normal position in which draw link 44 rests upon a cross bar 53 fixed within the frame F. The normal positions of sub-levers 36 are determined by abutment as at 54 with cross member 30. In their normal positions, the type bars 24 lie against an arcuate rest 55 supported within the frame F.

Each key lever 35 has pivoted thereto a pendent dog 57, Fig. 1, having a laterally bent lug 58. A spring 59 urges dog 57 counterclockwise so that the dog normally abuts a stop pin 60 on the key lever. Upon depression of a key lever 35, its dog lug 58 engages and depresses a lever arm 62 of the corresponding draw link 44 for lifting the latter about pivot 43 and engaging the dog 46 with snatch roll 47 for resulting printing stroke of the type-action, in which stroke the draw link lever arm 62 may leave the lug 58. Should the key lever 35 be kept down, the type action may nevertheless return fully to normal position because the key lever dog 57 is turnable clockwise, Fig. 1, to yield to the forward return of the draw link lever arm 62 to normal position.

A comb bar 63 fixed within the framework laterally spaces the draw link lever arms 62, and a comb bar 64 fixed to cross bar 53 laterally spaces and guides the draw-links 44, and its top edge is a rest for the draw-link dogs 46. A comb plate 65 fixed within the framework laterally spaces the key levers 35 and limits the upward movement of the latter. Restoring springs 67 for the key levers 35 are seated on adjusting screws 68 in a bar 66 fixed within the framework.

Computing mechanism

A plurality of totalizers, each comprising a set of accumulating wheels or order units 11, Fig. 1, may be distributed laterally in the computing base B. For each totalizer there is a set of pin bars 12 each having a row of depressible digit pins 13 and a drive rack 14 meshing with a companion idler 15. The pin bars are normally positioned by spring devices 16 against a comb guide 17 so that their pins 13 are out of line with corresponding pin setting bars 18, each of which is operatively connected to a rock shaft 19.

For each computing zone of its travel the typewriter carriage C carries a column unit 80 adapted to depress serially a series of denominational jacks 81. Each jack 81, when depressed, operates through connections 82 to move a corresponding master rack 83 in the computing base endwise. Associated with each set of pin bars 12 is a set of distributive racks 84, each connected to a corresponding master rack 83 by a rockable cross blade 85. Each set of distributive racks has a set of couplers 86 liftable by a plate 87 into operative alignment with the pin bars 12. Upon entry of the carriage in a computing zone, the column unit 80 selects and depresses one of three cam plates 88 to raise the corresponding coupler lifting plate 87 by means of operative connections, not shown, from said cam plate 88 to lifting plate 87, so that subsequent traverse of the jacks 81 by the column unit 80, for a given zone, will advance the pin bars 12 serially to pin setting positions under the pin setting bars 18. The serialim advance of the pin bars is effected consonantly with the letter feeding movements of the carriage as the numeral type actions are actuated, under control of their key levers 35, to type the amount to be indexed. The letter feed mechanism for the carriage will be described later. The pin setting arm 38 of each numeral type action sub-lever has a pendent rod 89 so that when said type action is operated to print its digit, the rod engages a crank 90 on the corresponding rock shaft 19 to rock the latter to depress the corresponding pin setting bar 18 and set the corresponding digit pin 13 in the pin bar 12 that stands advanced to pin setting position. The pin setting bars 18, rock shafts 19, and cranks 90 constitute an indexing mechanism by which the amount represented by the digits being typed is set up or indexed in the set of pin bars 12. The lengths of the sub-lever pin-setting arms 38 vary in proportion to the draw link arms 37 so that the pendent rods 89, guided at 160, have substantially uniform vertical strokes. The rods 89 are mainly vertical, and, therefore, some may have different horizontal extensions 89a, Figs. 3, 4, at which they are pivotally connected to the pin-setting arms 38.

In the letter-feed step of the carriage, which attends the typing of the last digit of an amount, the column unit 80 overrides and rocks a cyclic trip lever 91, partly shown, Fig. 1, on the framework. Said lever 91 in turn rocks a shaft 92, in the computing base, counterclockwise through a connection diagrammatically represented by the dot-and-dash line 93, Fig. 1. This retracts a latch arm 94 from a stud 95 fixed to a disc 96, and it results that the disc, spring urged, rotates slightly clockwise about a cycling shaft 97 journaled in the computing base. This slight rotation of disc 96 closes a clutch, not shown, to couple shaft 97 to the power drive, not shown, for a resulting revolution of said shaft. Just before the end of

this revolution which also turns the disc 96, the stud 95 will again encounter the restored latch arm 94 so that the disc 96 is arrested while the shaft 97 rotates slightly farther relatively to the arrested disc to cause the clutch to reopen to limit the rotation of said shaft 97 to one revolution or cycle. These power drive and control features may be substantially as described in my Patent No. 2,160,487, dated May 30, 1939.

10 By means of an operative connection, diagrammatically represented by the dot-and-dash line 98, Fig. 1, the cycle of revolution of shaft 97 reciprocates a general operator cross bar 99 in the computing base. In its advance stroke, cross bar 99 cooperates with the set digit pins 13 to advance the pin bars 12 to extents corresponding to the pins which were set. Means, not shown, cooperate with the cycling of shaft 97 to engage the order units 11 either with the racks 14 or idlers 15 as determined by operation of state control mechanism, not shown, prior to the cycling of the machine; said means also serve to disengage the order units 11 from the racks 14 or idlers 15 before the general operator cross bar 99, in its return stroke, restores the pin bars 12. The spring devices 16 restore the pin bars 12 slightly beyond the returned general operator cross bar 99 so that the latter in its normal position does not obstruct the serialim advance of the pin bars to pin setting positions.

Total printing control

A total key 100 has a key lever 101, of which there is shown, Fig. 1, the front key end and the rear end underlying a reed 102 vertically movable in the framework; the lever 101 is fulcrumed on a rod in the framework intermediate said ends. The raising of reed 102 from its normal position by operation of the total key lever 101 works through an operative connection, diagrammatically represented at 103, to raise and thereby disengage a carriage feed rack 104 from the escapement mechanism, later described, for resulting advance of the carriage toward the total printing zone. A carriage arresting stop 105, partly shown, Fig. 1, is operatively connected to a fork 102a of reed 102 and is engageable by a counterstop on the column unit 80, when lifted by reed 102, to arrest the carriage in such position that, the total key being released and reed 102 and stop 105 dropping back to normal position with attendant reengagement of the letter feed rack with the escapement, the carriage settles at the highest denomination position of the total printing zone.

55 The elevation of reed 102 by depression of the total key has also thrust rearwardly a rod 106, operatively connected to the cam plates 88 at 107, so that said cam plates are tilted to the dotted line positions, Fig. 1, where edges 107a of said cam plates 88 overlie and thereby become operatively connected to arms 108 extending rearwardly from three jacks 109 disposed to the right of the denomination jacks 81. Each cam plate 88 and its corresponding jack 109 represents one of the three totalizers which may be provided in the computing base. Each jack 109 has an operative connection to a corresponding cross blade 110, the operative connection being similar to the parts 82, 83 associated with the denomination jacks 81.

70 The column unit 80 for the total printing zone will have a tappet 111 to depress that one of the cam plates 88, the latter being in the dotted line positions, corresponding to the totalizer from which it is desired to print the total at said zone. 75 This depression of a cam plate 88 occurs just be-

fore the carriage reaches the position, corresponding to the highest order unit 71 at which it settles following operation of the total key and is attended by rocking of the corresponding cross blade 110 counterclockwise about its lower edge. Such rocking of any cross blade 110 operates through a connection diagrammatically represented at 112, Fig. 1, to rock a shaft 113 in the computing base clockwise and thereby retract a latch arm 114 on said shaft from stud 115 of an arm 116 fixed to a rock shaft 117 journaled in the computing base.

Each order unit 71 has a disc having notches that form ten digit stops 119, partly shown in Fig. 1. For each set of units 71 there may be a set of feelers 120 supported for endwise movements. Said feelers 120 are spring urged toward the order units and are normally held in retracted positions by a cross bar 121 supported and guided, by means not shown, for horizontal movements for receding from and for restoring said feelers 120. Said feeler bar 121 has operative connection, diagrammatically represented at 122, to rock shaft 117. Upon the retraction of latch arm 114 at advance of the carriage to the total printing zone, as a result of operation of total key 100, a spring 123 turns shaft 117 counterclockwise to a stop 118 so that, through connection 122, bar 121 is moved forwardly to recede from the feelers 120. Each feeler 120 has pivoted thereto an arm 125 spring-urged against a stop 127 on the feeler.

Associated with each set of feelers 120 is a set of interponent plates 128 supported and guided for vertical movements. Each set of interponents 128 is normally upheld by a cross rod 129 which in turn is upheld by means, including a latch device, not shown, controlled by a corresponding carriage-controlled cam plate 88 and its associated cross blade 110. Depression of a cam plate 88 and attendant rocking of its cross blade 110 releases said upholding means, including said latch device, and causes the corresponding set of interponents 128 to drop by gravity so that cam-points 130 of said interponents 128 each settle between two teeth of the corresponding pin bar rack 74. Such dropping of a set of interponents 128 also releases the corresponding set of feelers 120 for movement toward the order units 71 in that rollers 131 on the feeler arms 125 may pass over upper edges 132 of the dropped interponents 128. The other sets of interponents 128, remaining in upheld position, obstruct, by their rear edges, the neighboring rollers 131 so that the corresponding sets of feelers 120 cannot advance at recession of the bar 121 which occurs at carriage operation of a cam plate 88 while in its dotted line position, Fig. 1.

The released feelers 120 each settle against whichever digit stop 119 stands presented by the corresponding order unit 71, and thereby a tab 133 on each feeler arm 125 is positioned under and thereby selects one of a series of eleven cross blades 134, 135 supported by means, not shown, for vertical edgewise movements. There are ten of the blades 134 for the positions, from "0" to "9," of the order units. The eleventh blade 135 corresponds to the "9" position of the highest order unit 71 and assumes this position when the totalizer registers a credit balance or overdraft and the highest order unit presents a stop 119 to arrest the feeler 120 with its tab 133 under said credit balance blade 135. If a set of order units registers a debit, that is, positive amount, the highest order unit stands at "0" since the number of order units, say, nine units, may be

large enough so that a positive amount does not run to the highest order unit.

In summary, it may be stated that following operation of the total key 100 the carriage advances to the total printing zone, as defined by a column unit 80, and the carriage will settle at the position corresponding to the highest order unit 71. The selected set of feelers 120 also will have been released and become positioned with their tabs 133 under blades 134, 135 corresponding to the digits of the amount standing registered in the order units 71. As the carriage settles at this highest position, the column unit depresses the highest denomination jack 81 and there is attendant slight forward advance of the highest denomination pin bar 72 to bring its pins 73 under the pin setting bars 78. This slight advance of pin bar 72 acts against the cam 130 of the corresponding dropped interponent 128 and thereby lifts the latter. As the interponent 128 is lifted, its upper edge 132 engages the roller 131 of the companion feeler arm 125 and turns said arm clockwise to lift its tab 133 to lift the blade 134, or 135, under which said tab is positioned.

The above description of the mechanism whereby blades 134, 135 are capable of being selectively lifted under control of the order units 71 and carriage, subject to prior operation of total key 100, is believed sufficient for an understanding of the present invention, and further details may be along the lines shown in my Patent No. 2,192,365, dated March 5, 1940, and in my pending application Serial No. 337,380, filed May 27, 1940, now Patent No. 2,372,681, issued April 3, 1945, to which reference may be had.

Electro-magnet control of typewriter for total printing

Each blade 134, 135 has a tongue 137 to engage an insulator button 138, Figs. 4, 6, 11, secured to a lower contact blade 139 to which is secured a contact point 140, Fig. 13. An upper contact blade 141 has a contact point 142. One of the contact points 140, 142 may be convex-surfaced and the other may be flat-surfaced for wiping action. The several pairs of upper and lower contact blades 139, 141 may be spaced laterally apart, as in Figs. 11, 13, and the tongues 137, of course, have similar lateral spacing. Each lower contact blade 139 is clamped between upper and lower insulator bars 143, 144. The lower bar 144 may have cross slots 145 fitting the width and thickness of the lower blades 139, each of which may be secured against endwise displacement by a dowel 146 in the lower insulator bar 144. The upper contact blades 141 are integral with a conducting strip 147 which may rest upon the upper insulator bar 143 which in turn rests upon the lower contact blades 139. The lower insulator bar 144 is seated upon arms 149 of angular brackets 150 of which there may be three secured by screws 151 to the cross bar 63. Screws 152 secure the upper and lower insulator bars 143, 144 to said arms, the strip 147 having a clearance 153 so that contact with the grounded middle screw 152 is avoided. Intermediate screws 157, each disposed between two neighboring pairs of contact blades 139, 141, pass through and clamp together the strip 147 and insulator bars 143, 144 by clamp nuts 154. Cross bar 63 is secured to ears 155 of two side brackets 156, Fig. 11, each secured to the inner side walls of the typewriter frame F by screws 158 and dowels 159. A cross bar 160 secured to lateral

tabs 156 of brackets 156 is perforated to receive and guide the pin setter rods 89 of the numeral type actions. The contact blades 139, 141 are made of thin spring material such as phospho-bronze of a thickness, say, of .010 of an inch. Although the insulator buttons 138 are at different distances from the insulator bars 143, 144, each one of said contact blades is freely flexible, by little pressure against the buttons 138, to close its normally open contacts when the corresponding blade 134 or 135 is lifted. All the blades 134, 135 have equal extents of lift of, say, about eight hundredths of an inch and may immediately engage their insulator buttons 138. This extent of lift of a blade may be more than enough to close the contacts so that the latter, when closed, are given a wiping movement as the contact blades are flexed further by the excess lift of a blade 134 or 135.

For each of the ten numeral-type-action draw-links 44, there is an electro-magnet M, and for case shift draw-link 161, to be referred to later, there is a magnet SH, Figs. 1, 3, 4, 6, 12. Each of said magnets and a U-shaped frame 162 therefor are attached in a row to the underside of a channel bar 163 by screws 164 threaded into the magnet core. A cover plate 166 is secured to channel bar 163 by screws 167 threaded into studs 165 forming heads of three of the magnet screws 164. Said plate 166 has turned-down ends 168 secured to the inner side walls of the typewriter frame F by screws 169. A slot at each end of the cover plate fits a stud 170 in frame F to cooperate with screw 169 to keep the magnets and their supporting bar structure 163, 166 from turning.

Each magnet has an armature plate 171 having a fulcrum bearing against a lower edge 172 of the rear leg of the U-shaped frame 162. From said edge 172 extends a tongue 173 which loosely fits into a slot in the armature plate 171 to retain the latter transversely. A spring 174, attached to frame 162, upholds armature plate 171 against said edge 172 and normally keeps said armature plate separated from the bottom end of the magnet core 177 as an arm 178 of the armature plate 171 stops against the back of frame 162. An upturned tongue 179 at the forward end of the armature plate 171 underlies a land 180 at the rear end of the companion draw link 44 or 161.

When a magnet is excited, through closing its circuit as described later, it attracts its armature plate 171 and turns the latter about edge 172 to lift the draw-link 44 or 161, to engage the draw-link dog 46 with the rotating snatch roll 47 for resulting actuation of the type action or of the case shift mechanism. The front leg of the U-shaped frame 162 protects the magnet coil and may form part of the magnetic circuit.

Case shift mechanism

A case shift key lever 183, Figs. 4, 5, 6, may be fixed to a rock shaft 184 journaled in the typewriter frame brackets 156, Fig. 1. An arm 185, fixed to said rock shaft 184, has a pin-and-slot and spring connection 186 to a connecting-rod 187 pivotally connected at 188 to a slide 189 having slots 190 slidably fitting studs 191 in the typewriter frame F. An eccentric 192, Figs. 5, 7, rotatable about the axis of snatch roll 47 has pivoted thereto at 197 a clutch dog 193 urged, counterclockwise, Fig. 5, by a spring, not shown, toward the snatch roll. Dog 193 is normally held disengaged from snatch roll 47 by resting, as at Fig. 5, against a front stop 194 on slide 189.

Upon depressing the case shift key lever 183, its shaft is rocked counterclockwise and works through arm 185 and connecting-rod 187 to move slide 189 on studs 191 to retract stop 194 from dog 193, which consequently is spring-pressed into engagement with snatch roll 47, whereby the eccentric 192 is rotated counterclockwise, Fig. 5. Key lever 183 is kept depressed and hence the slide 189 is kept in position so that a second stop 195 of the slide intercepts dog 193 and thereby causes its disengagement from snatch roll 47 in order to stop the eccentric 192 after the latter has turned about one-half of a revolution. Upon releasing the shift key lever 183, a spring 196, attached to slide 189, restores the latter, together with the rest of the key lever train, thereby withdrawing the secondary stop 195 from dog 193 to allow the latter to again engage with snatch roll 47, whereby the eccentric 192 is turned counterclockwise to complete its revolution, the end of the revolution being determined as primary stop 194 of the restored slide 189 intercepts dog 193 and causes its disengagement from snatch roll 47.

25 A strap 198 journaled, as by ball bearings, not shown, upon eccentric 192 is pivotally connected at 199 to a rocker 200 rotatable about the same axis as a rock shaft 201 journaled in the typewriter frame F. Said shaft 201 has fixed thereto side arms 202 pivotally connected to side studs 203 at the lower side corners of a shift frame 205, Fig. 7, to which is attached type bar segment 26, Fig. 1. Rollers 209 have raceways in typewriter frame F and in shift frame 205 to further guide 30 the latter at its upper side corners. Rocker 200 may bear loosely on shaft 201 and has abutment screws 204 bearing on opposite sides of one of the studs 203 to connect operatively said rocker 200 to shift-frame 205. It will be seen now that the 35 first half revolution of eccentric 192, resulting from depression of case shift key lever 183, operates through strap 198 and rocker arm 200 to lower shift-frame 205 and type-bar-segment 26 to upper case position; and upon release of the 40 case-shift key-lever 183, the resulting completion of revolution of eccentric 192 raises and restores frame 205 and type-bar-segment 26 to normal or lower case position. Stops 211, Fig. 7, may be provided to engage and arrest the frame 205, 45 said stops augmenting the case-shift limiting action of cam 192 to assure more accurate arrest of said frame, its type bar segment 26 and type bars 24 in upper and lower case positions. The strap 198, rocker 200 and associated connections to the frame 205 may have inherent yield 50 sufficient to allow stops 211 to determine the exact case-shift positions. Springs 211^a counterbalance the weight of frame 205 and its attachments.

55 60 A lever 206, Figs. 4, 5, 6, fulcrumed on rod 32, is located in its slot 31 of cross member 30. Said lever 206 normally abuts cross member 30, as at 54, and has pivoted at 207 the case shift draw link 161. Like the draw links 44, the case shift draw link 161 has a toothed dog 46 and also has a restoring spring 52 and normally rests on cross bar 53, within the comb bar 64. A roll 208 on an arm of said lever 206 is operable against a cam edge 210 of an arm of case shift key lever 183.

65 70 Upon exciting the case shift magnet SH, as will be explained later, its armature plate 171 is attracted to lift the case shift draw link 161 to engage dog 46 thereof with snatch roll 47. The resulting rearward stroke of draw link 161 rocks counterclockwise the lever 206 which, in turn,

through the roll 208 and cam edge 210, rocks the case shift key lever 183 counterclockwise to operated position.

A rod 212 is pivoted at 213 to lever 206 and has its other end 214 slidably forked over a rock shaft 215 journaled in frame F. A latch lever fulcrumed on shaft 215 comprises arms 216, 217 and has pivoted thereto at 218 a thrust rod 219 guided in and projecting below a bracket 220 fixed to typewriter frame F. A spring 222 anchored to bracket 220 urges thrust rod 219 downwardly to turn clockwise the latch lever 216, 217 whose edge 223, however, normally bears against the underside of a square stud 224 fixed to rod 212. When the snatch-roll-driven stroke of said draw link 161 has rocked lever 206 counterclockwise to move the case shift key lever 183 to operated position, the rod 212 has shifted to permit latch lever 216, 217 to be rocked clockwise by spring 222 to position in which a latching recess 225 of arm 216 interlocks with stud 224 to keep the lever 206, and hence the case shift key lever 183, in operated position, until released as will be explained later.

In its rearward stroke, the case shift draw link 161 may encounter its knock-off screw 51 to become disconnected from snatch roll 47 just before lever 206 and case shift key lever 183 reach their fully operated positions which they may attain by the momentum of the parts.

Due to this movement of the case shift lever 183 to operated position and to the maintenance of said position by means of latch lever 216, 217, the eccentric 192 will have received its first half revolution by snatch roll 47 and will then be arrested by stop 195 of slide 189 which is also maintained in operated position, along with case shift key lever 183, and the type bar segment 26 and type bars 24 will thereby have become lowered to and will be maintained in upper case position until the above-mentioned release is effected.

Letter feed mechanism

Feed rack 104 on carriage C engages a pinion 228 ratchet-coupled to an escapement wheel 229 by spring-pressed pawl or pawls 226, Fig. 4, on said wheel. A dog rocker 230, Figs. 1, 4, 7, 8, swingable about pivots 231 includes a holding dog 232 and a stepping dog 233 pivoted on a stud 234 in dog rocker 230. A spring motor 235, on the machine frame, has a draw-band-connection to carriage C and tends to advance the carriage which is normally stopped by engagement of escapement wheel 229 with stepping dog 233 which rests against a stop 237 on dog rocker 230. The escapement wheel 229 and pinion 228 are journaled, and the dog rocker pivots 231 are mounted, in an escapement bracket 238, partly shown, supported by the machine frame F. A rocker frame comprising a cross bar 239 and upright arms 240 is fulcrumed at its opposite sides on studs 241 in bracket 238. A cross rod 242 spans said arms 240. The letter feed mechanism parts so far described are substantially as in the Underwood standard typewriter, see, for example, the Helmond Patent No. 1,516,922, dated November 25, 1924.

Side arms 243 pivoted to said rocker frame at 244 are integral with a cross piece 245 having a turned-down ear 246 which, with its attached collar 247, slidably fits a guide rod 248 which is fixed in bracket 238 and cooperates with the rocker frame 239, 240, 242 to support and guide the frame 243, 245 for fore-and-aft movements.

From the cross piece 245 adjustably projects a screw stud 249, Fig. 4, to engage dog rocker 230.

Shift frame 205 has arms 251 which rockably support, by means of pivot studs 250, a frame comprising arms 253 and 254 rigidly connected by a cross bar 255. An upper cross rod 256 may project through said arms 253, 254 to support pivotally side arms 258 fixed to a curved universal bar 259. Fingers 258a project from side arms 258 and slidably fit openings 257, Fig. 7, in the shift frame 205 to cooperate with the frame 253-256 for supporting the universal bar 259 for engagement and movement by heels 260 of type bars 24, the type bar segment 26 having a recess 261, Fig. 1, to admit the universal bar 259 for engagement by said type bar heels 260. In the normal positions of the parts, the front face 282 of a block 263 fixed to cross piece 245 may bear against cross rod 256 and the front edge of the universal bar 259 may bear against the vertical wall of recess 261 under the urge of a spring 264 attached to a stud, Fig. 4, of cross piece 245, the other end of said spring having attachment, not shown, to frame 205.

The universal bar 259 and its rockable supporting frame 253-256, being supported on shift frame 205, move up and down with the case shifts; but the dog-rocker-actuating frame 243, 245 does not partake of the case shift movements, in that it is supported on the main frame F. However, said frame 243, 245 is, by means of its face 262 which adjoins rod 256, always in operative connection with universal bar 259 irrespective of the case shifts, and it will be seen that such operative connection does not interfere with the case shifts.

Escapement switch

A switch 265, Figs. 6, 7, 8, 9, provided for a purpose to be described later, has a casing 265b secured to the side of a housing 252 containing cam plates 88 and jacks 81, Fig. 1, and secured to the typewriter framework F. Said switch is illustrated diagrammatically, Figs. 8, 9, and may include a snap device, not illustrated, whereby a small inward movement, say, of about one-thousandths of an inch, of a plunger 265c in said casing, closes the switch with a snap and whereby, conversely, release of the plunger results in a similar small outward movement thereof and a snap opening of the switch. A control lever 267 for said plunger may be a resilient strip fastened at its lower end to said casing. A rod 268 loosely fits in the upper end of lever 267 and has a sleeve 268a for shoulder engagement with said lever.

Rod 268 links lever 267 to an arm 269 fixed to a rock shaft 270, Figs. 7, 8, 9, journaled in a bracket 270a fixed to the escapement bracket 238. An arm 271 fixed to shaft 270 is engageable by an arm 272 of a lever fulcrumed on pivot stud 234 of escapement stepping dog 233 and having an arm 273 bent horizontally for engagement with the edge of said dog 233. Normally, dog 233 stops against stop 231, Fig. 8, of dog rocker 230 and in turn stops a tooth of escapement wheel 229 to hold the carriage in a letter-printing position. In its normal position, Fig. 8, dog 233 bears on arm 273 of the lever which, in turn, bears with its other arm 272 on arm 271 of shaft 270 to hold the latter in position wherein arm 269 and rod 268, with its sleeve 268a, press switch lever 267 to keep the switch plunger 265c in closed-switch position. In the usual letter space operation, dog rocker 230 is first rocked counterclockwise to the Fig. 9 position to withdraw stepping dog 233 from

its engagement with the escapement wheel tooth and interpose the holding dog 232 to hold the escapement wheel and carriage. Urged by its spring 274, the withdrawn dog 233 swings clockwise about stud 234 to a stop 235, partly shown, on the escapement bracket 238 to position dog 233, Fig. 9, for the next escapement wheel tooth. This clockwise movement of dog 233 is attended by corresponding movement of the train, comprising 273, 272, 271, 270, 269, and 268, to release switch lever 267 and plunger 265^c for consequent automatic snap-opening of switch 265. A spring 276, acting on arm 269, may cooperate to urge said train to switch-opening position. By return rocking of the dog rocker 230, the holding dog 232 is withdrawn from the escapement wheel and the stepping dog 233 is placed before the aforesaid next tooth. In the ensuing step movement of the carriage by its spring motor 235, the escapement wheel 229 is turned clockwise, Fig. 9, and rocks dog 233 counterclockwise back to stop 237, Fig. 8, which limits the carriage step. This counterclockwise rocking of dog 233 operates the aforesaid train to operate switch lever 267 to press the switch plunger 265^c so that switch 265 will be closed at the end of the letter feed step of the carriage. The movement of rod 268 derived from dog 233 may be in excess of the required movement of switch lever 267; this conduces to effecting the closing of the switch at the latter part or end of the carriage step movement.

Switch 265 is also opened and reclosed in correlation with tabulating the carriage. Upon lifting rack 104 from engagement with the escapement pinion 228 to release the carriage for tabulating, said pinion 228 and escapement wheel 229 become free to rotate; and, hence, stepping dog 233, which is in engagement with wheel 229 and is urged by spring 274, turns clockwise and turns wheel 229 counter-clockwise of Fig. 8 to a check-pawl 271, pivoted on dog rocker 230 and shown in Fig. 4. This clockwise turning of dog 233 causes opening of switch 265. When rack 104 is reengaged with pinion 228 at the end of the carriage tabulating movement, the carriage, under the urge of its spring motor 235, turns pinion 228 and escapement wheel 229 clockwise of Fig. 8, and thereby stepping dog 233 is turned counterclockwise back to stop 237 and causes reclosing of switch 265 as the carriage settles in its tabulated-to position.

Further, any movement of the carriage C in return direction rotates pinion 228 counterclockwise, Fig. 8, and, coincidentally, stepping dog 233 is rotated clockwise by spring 274 so that switch 265 is caused to be open during the carriage-return movement. At the end of the carriage-return effort, the carriage is urged again in advance direction by its spring-motor 235, and turns pinion 228 and escapement wheel 229 clockwise, thereby bringing dog 233 back to stop 237, Fig. 8, and coincidentally operating the aforesaid train to reclose switch 265. The switch-opening movement of dog 233 as an incident to carriage-return movement may be stopped by the above-mentioned check-pawl 271 on dog rocker 230, Fig. 4, arresting wheel 229 in its counterclockwise movement which attends said movement of dog 233. If check-pawl 271 is omitted, said movement of dog 233 may be checked by stop 275.

Operating zero type action under totalizer control without printing to advance carriage to first significant digit position for positive total

If a totalizer registers a positive total, the 75

highest order unit 71 stands at "0" and one or more of the next lower units may also stand at "0." For example, if the total is 70 42, the nine order units correspondingly stand at 0000070 42.

5 In the section entitled "Total printing control," it was explained that depression of the cam plate 88 for said totalizer is effected by the carriage just before the carriage, released for tabulating advance by operation of total key 100, reaches the position of highest denomination at which it finally settles. It was also explained that said depression of cam plate 88 causes release of rock shaft 117 and release of the feelers 120, for said totalizer, which feelers consequently move 10 and settle in total-reading positions against digit stops 118 so that their movable tabs 133 stand under those digit blades 134 that correspond to the digit-registering positions of the order units 71. The tab 133 of the feeler for the highest unit, which, in the above example, registers "0," is 15 lifted, by means of interponent 128, by the slight advance of the corresponding pin bar 72 occurring as the carriage settles at the highest denomination and depresses the corresponding jack 81. This lifting of tab 133 lifts the "0" blade 134 to bring the corresponding contact blades 139, 141 together and thereby excite the "0" magnet M for resulting actuation of the "0" type action sub-lever 36 from which the "0" type bar 24 has become disconnected as will now be described.

20 The "0" sub-lever 36 comprises two parts 278, 279, Figs. 1, 3, both fulcrumed on rod 32. These parts may be received in one corresponding slot 31 of cross member 30. The "0" key lever 35 is 25 also fulcrumed on rod 32, between the parts 278, 279, as is provided for by an offsetting bend 280 in the part 278. A lever 281 pivoted on part 278 at 282 has one arm having a headed stud 283 which is normally within a slot 284 of the other part 279 whereby these parts are normally coupled for joint movement about fulcrum rod 32. A spring 285, connected between part 278 and lever 281, urges the latter counterclockwise to keep said parts 278, 279 coupled. A link 286 connects the other arm of lever 281 to an arm 287 connected by a yoke 288 to another arm 289 to form a lever 290 loosely fulcrumed on the shaft 215 journaled in the framework. Suitable collars, not shown, on shaft 215 may retain lever 290 laterally. A lateral tab 292 of arm 289 has a slot 293 through which passes a control rod 294 extending forwardly from tab 292 to a pivotal connection 295 with a link 296 whose upper end is pivotally supported on the right-hand one of the pivot studs 250, on shift frame 205, 251, for the rear universal bar frame 253—256. An arm 297 of said frame presents a stud 298 below pivot 250 for engaging a rear edge 299 of link 296. A rod 300, pivotally connected at 301 to control rod 294, depends from the latter through a guide 302, Fig. 1, on the framework and has a roller 303 to abut the top of a rod 304 projecting above a guide 305 in computing base B. The lower end of rod 304 is pivotally connected at 306 to an arm 307 fixed to rock shaft 117.

30 A spring 308 connected between a lateral ear 309, arm 289, and control rod 294 tends to turn lever 290 clockwise on shaft 215 so that rod 300 bears upon the lower rod 304, and spring 308 tends 35 to move the control rod 294 so that edge 299 of link 296 bears against stud 298 of supporting frame 254—256 for universal bar 259.

40 It will be seen now that as shaft 117 is released and consequently is rocked counterclockwise to stop 118 by spring 123 preparatory to total

printing from a totalizer, the lower rod 304 and the rod 300 bearing thereon are lifted, and control rod 294 is thereby turned counterclockwise about its pivotal connection 295 with link 296. This rotates the lever 290 counterclockwise about shaft 215 to operate through link 286 to turn the coupling lever 281, on sub-lever part 278, clockwise to raise stud 283 out of slot 284 of the other sub-lever part 279, thereby disconnecting said parts 278, 279. The part 278 is connected by link 42 to the "0" type bar 24, and, hence, the described disconnection at 283, 284 operatively disconnects said "0" type bar from the part 279 which remains operable by its draw link 44.

The rock shaft 117 remains in its rocked position against stop 118 until restored, at the end of total printing, by cycling the general operator in the computing base; and, correspondingly, as far as rock shaft 117 is concerned, the coupling 283, 284 remains disconnected. The sub-lever part 279, operable counterclockwise through its draw link 44 by snatch roll 47, is connected at 311 to a link 312 which has a pin-and-slot or one-way driving connection 313 to an arm 314 fixed to a rock shaft 315 journaled in the framework. An arm 316 also fixed to shaft 315 has a pin-and-slot connection 317 to a lever arm 318 extending from rocker frame 239, 240 to which is connected the frame 243, 245 which has operative connection to the escapement dog rocker 230.

As the sub-lever part 279 is operated, counterclockwise, through its draw link 44, by snatch roll 47, consequently to the described lifting of the "0" blade 134, the rock shaft 315 is concomitantly rocked counterclockwise through link 312 and, in turn, through the pin-and-slot connection 317 the frame 239, 240, Fig. 1, is rocked clockwise to move frame 243, 245 to rock the escapement dog rocker 230 clockwise. As this occurs, the draw link 44 for sub-lever part 279 becomes or has become disconnected from snatch roll 47 by encountering its knock-off screw 51, and it results that the described train of parts to the escapement dog rocker 230 is spring restored and said escapement dog rocker 230 is spring returned counterclockwise to normal position. The first or clockwise rocking of escapement dog rocker 230 has released its stepping dog 233 from the escapement wheel 229 for resulting stepping movement of said dog 233, and the second or counterclockwise rocking of said dog rocker 230 has again interposed the stepping dog 233 to the escapement wheel which thereby turns with attendant letter feed step of the carriage.

This letter feed step of the carriage causes the latter to leave the highest jack 81 and depress the jack 81 of the next lower denomination for which the order unit 71 also stands at "0," according to the above example, 0000070 42, and causes the sub-lever part 279 to be again operated by snatch roll 47, without printing "0," thereby causing a further letter feed step of the carriage. And so on, the carriage is advanced step by step, as determined by each order unit 71 that registers an insignificant "0," until the carriage arrives at the denominational position and depresses the jack 81 corresponding to the order unit that registers the first significant "7" in the above example.

Because of the resulting energization of the "7" magnet M, the "7" type action is connected to and operated by snatch roll 47 to print the first digit "7" and index "7" in the corresponding pin bar 72 by means of the indexing rod 89 and pin-setting bar 78. In printing, the "7" type bar 24 engages and moves rearwardly the universal bar

259 and rocks frame 253—256, Fig. 4, clockwise, which moves frame 243, 245 to rock the escapement dog rocker 230 clockwise. The attendant movement of frame 239, 240, 318, and shaft 315, however, will not move link 312, because the one-way driving connection 313 is provided.

As universal bar 259 is moved rearwardly by operation of the "7" type bar 24, the arm 297, 298 of frame 253—256, which is rocked clockwise, 10 rocks the link 296 clockwise, Fig. 3, and thereby draws control rod 294 forwardly to withdraw its upper step 319 from tab 292 of lever 290 and permits said tab 292 to fall upon a lower step 320 of said control rod 294 which remains upheld by rods 300, 304. The resulting clockwise rotation of lever 290, movement of link 286, and counterclockwise rotation of lever 281 by springs 285, 308, enter stud 283 into slot 284 again, and thereby the parts 278, 279 of the "0" type action sub-lever are coupled again so that the "0" type bar 24 is made operative again in order to print "0" upon any subsequent selection and operation of the "0" type action following the typing of the first significant digit "7," in the above example.

The "7" draw link 44 encounters its knock-off 25 51 and becomes disconnected from snatch roll 47 so that the "7" type action completes its printing stroke by momentum and thereupon returns, with attendant return of universal bar 259 and counterclockwise return of dog rocker 230. At the clockwise and counterclockwise movements of dog rocker 230, at the printing and return strokes of the "7" type action, the escapement dogs 232, 233 function relatively to escapement wheel 229 to effect a letter feed step of the carriage to the next 30 lower denomination for which the order unit 71 stands at "0," in the above example, and hence determines that the "0" type action, whose sub-lever parts 278, 279 have become recoupled, is operated to print "0" and effect, by substantially 35 joint operation, of universal bar 259 and link 312, a letter feed step of the carriage. This step of the carriage may bring a suitable skip device, not shown but which may be as described in the aforesaid Patent No. 2,192,365, into play so that an additional advance of the carriage automatically occurs to the tens of cents denomination for which the computing pinion registered "4," in the above example, so that now the "4" type action 40 is caused to be operated to print and index "4" and the carriage is letter spaced another step. Thereupon, as will now be clear, the "2" type action is automatically caused to be operated to print and index the last digit "2" of the above 45 example.

In the letter feed step which attends the typing of the last digit, the carriage overrides cycle trip lever 91 for a resulting one revolution cycle of the general operator shaft 97 in the computing 50 base. Said shaft 97 has an operative connection 60 diagrammatically represented at 322, Fig. 1, to the rock shaft 117 to restore the latter clockwise to the position where it becomes held again by latch 114. The restoration of shaft 117 operates 65 through connection 122 and cross bar 121 to restore feelers 120. The restoration of shaft 117 is also attended by dropping of rod 304, thereby permitting the rod 300 to also drop and control bar 294 to turn clockwise about pivotal connection 295, under the influence of gravity and oblique spring 308, and then to move rearwardly, under influence of said spring 308, to bring the upper step 319 under the top of the slot in tab 292 of the previously restored lever 290. Until 70 control rod 294 has been thus restored, a shoulder 75

324 thereof has rested against the front of tab 292 of previously restored lever 290.

When "0" sub-lever parts 278, 279 are coupled and operated jointly about rod 32, the lever 281, of course, also turns bodily about rod 32. As will be evident from Fig. 1, the pivotal connection 321 of lever 281 to link 286 is so disposed that its movement about rod 32 is merely idle and substantially does not affect the coupling lever 281 or the lever 290.

Operating "9" type action under totalizer control without printing to advance carriage to first significant figure position for overdraft total

For an overdraft total, the highest order unit 71 of the totalizer registers "9" and one or more next lower units may also register "9" since the nines complement of the true overdraft stands registered in all the nine units. For example, if the true overdraft is 60 17, the units will stand at 9999939 82. A fugitive-1 mechanism, not shown, but exemplified in my aforesaid Patent No. 2,192,365 causes the lowest order unit to stand at the nines complement of the true overdraft digit of lowest denomination. At automatic total printing, the "9" type action is to be selected and operated without printing for each of the five highest order units 71 registering an insignificant "9" in the above example, in order to index "9" and to advance the carriage a step for each of said five units. This advance of the carriage brings it to the denomination for the unit that registers the first significant digit which, in the above example, is "3" or the complement of the first true overdraft digit "6." By initially operating the case shift mechanism, the type actions selected in accordance with the nines-complement digits registered in the units 71 may print the true overdraft since each numeral type bar has an upper case digit-type which is the nines-complement of its lower case digit-type. The "0" type action has the lower case digit-type "0" and the upper case digit-type "9"; the "1" type action has the lower case and upper case digit-types "1" and "8," respectively, and so on to the "9" type action which has the lower case and upper case digit-types "9" and "0," respectively.

Preparatory to printing an overdraft total, the total key 100 is depressed to release the carriage for resulting advance to the position, in the total printing zone, corresponding to the highest order unit 71, the carriage settling at said position as hereinbefore described. Just before reaching this position, the carriage will have depressed the cam plate 88 corresponding to the totalizer from which the total is to be printed so that the corresponding set of feelers 120 will assume total reading positions against stops 119 on the units. The depression of said cam plate 88 releases shaft 117 which rocks counterclockwise to release said feelers. Since the highest unit 71 stands at "9," it presents a stop 119 to arrest its feeler 120 with the tab 133 thereon positioned under blade 135. The slight advance of the highest pin bar 72 by the carriage depressing the highest jack 81, as the carriage settles in said highest position, lifts tab 133 by means of interponent 128 so that said blade 135 is also lifted to bring the corresponding two contacts 139, 141 together to close a circuit, hereinafter described, to excite case shift magnet SH.

The excited magnet SH attracts its armature plate 171 to lift the case shift draw link 161 to engage dog 46 thereof with snatch roll 47. The

resulting rearward stroke of draw link 161 rocks lever 206 and case shift key lever 183 counterclockwise to operated positions; and, correspondingly, slide 189 is shifted forwardly to retract its stop 194 from, and thereby release, clutch dog 193 to engage snatch roll 47 so that the latter drives eccentric 192 through one-half revolution as determined by the disengagement of said dog from the snatch roll upon interception of the dog by the second stop 195 of the forwardly shifted slide 189. This half revolution of eccentric 192 works through strap 198 and rocker arm 200 to lower shift-frame 205 to upper case position which is maintained, pending later release, by reason of rod 212 having been pulled forwardly by lever 206 and interlocked with latch lever 216, 217 to block return of levers 206, 183 and slide 189, all as hereinbefore described under the heading "Case shift mechanism."

20 *Suppressing operation of the "9" type bar*

An arm 323 fixed to rock shaft 215 has a stud 325 normally held against a rear edge of rod 212 by a spring 326 connecting said stud and a stud on rod 212, Figs. 4, 6, whereby the counterclockwise rocking of lever 206 rocks said shaft 215 counterclockwise. This interposes a stop 327, on an arm 328 fixed to said shaft 215, below a shoulder 329 on an arm of a lever 330 loosely fulcrumed on an extension 203^a threaded upon the shank of the right-hand stud 203 on shift frame 205, as in Fig. 7. Lever 330 is located between spacing collars 331 fixed to extension 203^a and is urged clockwise by a spring 332 anchored to one of said collars so that an edge 333 of a forwardly extending arm of said lever 330 normally bears against the underside of a cross rod 334 supported within the typewriter frame F. The stud extension 203^a, being on shift frame 205, is movable with the latter downwardly a distance equal to the case shift. At the initial portion of said downward movement of stud 203, the edge 333 of lever 330 continues to bear against rod 334 under the influence of spring 332, whereby said lever turns clockwise about rod 334 as a fulcrum until the shoulder 329 on the rear arm of said lever 330 rests on the interposed stop 327. Then as the downward case shift movement of shift frame 205 and its said stud extension 203^a is completed, the lever 330 is turned counter-clockwise about the interposed stop 327 as a fulcrum to depress the forward arm of said lever 330 so that a stud 335 thereon descends and engages an arm 336 of a lever 337 and rocks said lever clockwise about its pivot 338 on one part 339 of the "9" type action sub-lever 36. This clockwise rocking of lever 337 withdraws a stud 340 thereon from a slot 341 in another part 342 of the "9" type action sub-lever, whereby said part 342 which has a draw link 44, and a rod 89 for operating the "9" pin setter, is operatively disconnected from the other sub-lever part 339 which is connected by link 42 to the "9" type bar 24. The "9" sub-lever parts 339, 342 and the fulcrum end of the "9" key lever 35, disposed between said parts, are fulcrumed on rod 32 and are received in a slot 31 of cross member 30. Lever 337 and sub-lever part 339 are connected by a spring 343. It will be seen now that the "9" sub-lever parts 339, 342 and their coupling lever 337 are similar to those hereinbefore described for the "0" type action sub-lever.

Disabling and reenabling the "0" type bar preparatory to overdraft total printing

Inasmuch as rock shaft 117, Fig. 1, becomes

rocked counterclockwise, to release feelers 120, just before the carriage reaches the highest denominational position in respect to overdraft printing, it operates as hereinbefore described to lift control bar 294 counterclockwise about its pivotal connection 295 to link 296, and thereby lever 290 is rocked counterclockwise and disconnects parts 278, 279 of the "0" type action sub-lever and renders the "0" type bar 24 inoperative.

Nevertheless, the "0" type action must be restored to printing effectivity by reconnecting its said disconnected parts 278, 279 before operation of any of the numeral type actions occurs for overdraft total printing. The reason for this is that the first, or any other, significant figure of the true overdraft total may be a "9," which stands in the totalizer as "0." This figure is printed by the "0" type action, using the upper case or "9" type. The reconnection of said parts 278, 279 is effected as follows: As the shift frame 205 is moved downwardly to upper case position, a lower cam edge 344 of link 296, Fig. 3, pivoted on frame 205 and connected to control rod 294, engages and is deflected by a rod or stud 345 supported in the framework. The link 296 is thereby rocked clockwise about its stud 250 to draw control rod 294 forwardly to withdraw its upper step 319 from tab 292 of lever 290. It results that lever 290, link 286 and "0" coupling lever 281 return to normal positions, as urged by springs 285, 308, and effect reconnection of the "0" sub-lever parts 278, 279. It will be apparent now that the case shift operation of magnet SH under control of the highest order unit 71 registering overdraft "9" serves to effect disconnection of the "9" type bar from its operating train and reconnection of the previously disconnected "0" type bar to its operating train.

Circuit control by case shift

Two outer resilient contact blades *a*, *c*, and a middle resilient blade *b* may be mounted on and insulated from the side of housing 252, Figs. 4, 6, and from each other. The shift frame stud 250, which carries link 296, also pivotally supports a lever 347 whose upstanding arm is operatively connected by a rod 348 to the middle contact blade *b* which has a set so as to be normally in contact with the front contact blade *a* and out of contact with the rear contact blade *c*. This normal contacting of blades *a* and *b* obtains when the shift frame 205 is in upper position, for lower case typing, so that when the blade 135 in the computing base is lifted under control of the highest order unit registering the overdraft "9" and brings the corresponding contact blades 139, 141 together, a circuit is made to excite the shift magnet SH. The resulting lowering of shift frame 205 to upper case position lowers the lever 347 so that a cam edge 349 on a depending arm thereof engages, and is deflected by, stud 345 to rock said lever 347 clockwise and push the rod 348, whereby the rod sleeve 348a shoulders the middle blade *b* out of contact with the front blade *a* and into contact with the rear blade *c*, as the case shift is completed. The circuit to the case shift magnet SH, which has done its work, is thereby broken, and, instead, through the contact blades 139, 141 which are still together and the now closed contact blades *b* and *c*, a circuit is made to the "9" magnet M to excite the latter.

Said "9" magnet, when thus excited, causes the "9" draw link 44 to be connected to and operated by snatch roll 47 to rock the "9" sub-lever part 342 counterclockwise to set the "9" pin 72 in the

highest pin bar 72. A link 350 pivoted to said sub-lever part 342 has a one-way drive connection 351 to an arm 352 fixed to rock shaft 315 so that the latter is also rocked counterclockwise. The

5 "9" draw link 44 finally encounters its knock-off 51 and becomes disconnected from snatch roll 47, whereupon the "9" sub-lever part 342 and its draw link 44 may complete their strokes by momentum and are then spring restored to normal positions. The counterclockwise rocking of sub-lever part 342 operates through the train; namely, rock shaft 315, connected arms 316, 318, frame 239, 240, and frame 243, 245, to rock the escapement dog rocker 230 clockwise. Conversely, when said sub-lever part 342 is restored clockwise, said train is spring restored and escapement dog rocker 230 is spring restored counterclockwise.

The described rocking of escapement dog rocker

20 230 results in a letter feed step of the carriage to the next lower denomination for which, according to the above example, the unit 71 registers an insignificant "9." At said next lower denomination, the carriage depresses the corresponding denominational jack 81 to slightly advance the corresponding pin bar 72. Since said next lower unit registers "9," its feeler 120 is positioned with its tab 133 under the "9" blade 134 so that said slight advance of said next lower pin bar 72 lifts said "9" blade 134. It may be noted here that all the units 71 below the highest denomination determine selection of said "9" blade 134 if they stand at "9," and that it is only the highest unit, standing at "9," that can determine selection of the case shift blade 135, the digit stops 119 on the units being arranged accordingly. The lifting of the "9" blade 134 brings its contacts 139, 141 together to excite the "9" magnet M. It results that the "9" sub-lever part 342, still disconnected from the "9" type bar 24, is again operated, without printing, to index "9" and cause another letter feed step of the carriage.

45 As will be understood now, the operation of the "9" sub-lever part 342, without printing, is automatically repeated for each unit 71 that registers an insignificant "9" of an overdraft; and, correspondingly, each insignificant "9" is indexed and the carriage is advanced step by step to the position corresponding to the unit 71 that registers the first significant figure "3" in the above example, namely, 9999939 82. At this position, the "3" blade 134, having been selected, is lifted and brings its contacts 139, 141 together to excite the "3" magnet M and thereby cause operation of the "3" type action to index "3" in the corresponding pin bar 72 and at the same time print "6," which is the first digit of the true overdraft.

60 The printing stroke of any type bar 24 to print the first true overdraft digit moves the escapement universal bar 259 rearwardly and rocks its frame 253—256 clockwise in order to effect the letter feed step of the carriage. As said frame 253—256 is rocked clockwise, its stud 298, which has been lowered along with shift frame 205, engages a cam edge 354 of a bell crank 355 and rocks the latter counterclockwise on its fulcrum stud 345. Said bell crank 355 has a pin-and-slot connection 356 to an arm 357 fixed to shaft 215, and, therefore, said shaft 215, which had previously been rocked counterclockwise, is also rocked clockwise to withdraw the stop 327 from shoulder 329 on lever 330. At this clockwise rocking of

shaft 215, the arm 323 thereof, being connected to spring 326, stretches the latter idly since the rod 212 to which said spring is connected is still held by the latch lever 216, 217. It results from the clockwise rocking of shaft 215 that said lever 330 is released and is immediately turned clockwise by its spring 332 about stud extension 203a on the still lowered shift frame 205. This clockwise rocking of lever 330 is stopped by cross rod 334 and raises its stud 335 to release the coupling lever 337 so that the latter is turned counterclockwise by its spring 343 to enter its stud 340 into slot 341 and thereby reconnect the "9" sub-lever parts 338, 342 and so render the "9" type action again operative to print. At forward return of universal bar 259 with recoil of the type bar, the stud 298 recedes from cam edge 354 of bell crank 355. This permits the stretched spring 326 to turn shaft 215 counterclockwise until stop 327 bears on the back edge of lever 330 above the shoulder 329.

The sub-lever part 342, Figs. 4 and 6, has a land 358 which may be concentric with fulcrum 32, and the front edge of the slot 341 extends substantially above said land so that said land and front edge afford guides into the slot 341 for the pin 340. The other sub-lever part 339 may have a stop edge 353 upon which pin 340 may rest instead of resting upon the bottom of slot 341 in the normal positions of the parts. The "0" sub-lever parts 278, 279, Figs. 1, 3, may have similar formations.

By the letter-feed-step of the carriage which attends the printing of the first true overdraft digit "6," the position corresponding to the next lower unit 71, which stands at "9," is reached, and it results that the "9" magnet M is again excited so that the "9" type action, whose parts 339, 342 have become reconnected, is operated to index "9" and print "0" by its upper case type, the type bar system being still in upper case position. The attending letter feed step of the carriage and the cooperation of the skip device, not shown, for skipping the punctuation space bring the carriage to the position for the next unit 71 which stands at "8," and it results that the "8" magnet M becomes excited and the "8" type action becomes operated to index "8" and print the upper case "1." In a similar way, for the last overdraft digit, the "2" magnet M becomes excited and the "2" type action becomes operated to index "2" and print the upper case "7."

In the letter-feed-step which attends the typing of the last digit, the carriage overrides the cycling trip lever 91 for a resulting cycling operation of the general operator mechanism in the computing base. In this cycling operation, the pin bars 72 indexed with the overdraft complement 9999939 82 are operated to rotate the order units 71 subtractively, by means of the idlers 73, to clear them.

Restoration to lower case

A cam disc 359, Fig. 6, fixed to cycling shaft 97 is engaged by a spring-pressed follower arm 360 fulcrumed in the computing base. A link 361 connects said arm 360 to an arm 362 fixed to a rock shaft 363 journaled in the framework of the machine. An arm 364, fixed to said shaft, has a stud 365 under the thrust rod 219. At the initial part of the cycle or clockwise rotation of cam disc 359, a cam rise 366 rocks clockwise the follower 360 which, through the described connections moves thrust rod 219 upwardly to rock the case shift latch lever 216, 217 counterclockwise

to disengage it from stud 224 of rod 212. It results that rod 212 moves rearwardly, lever 286 turns clockwise, and draw link 161 moves forwardly to bring these parts, shaft 215, its arms 323, 328, and bell crank 355, to normal position under the influence of springs 52, 326. At this clockwise return of lever 286, the case shift lever 183 rocks clockwise, and slide 188 moves rearwardly to normal position under influence of spring 196, thereby withdrawing stop 195 on said slide from clutch dog 193 to allow the latter to engage snatch roll 47, whereby eccentric 192 is turned a half revolution or until said pawl is intercepted by the primary stop 194 of the restored slide 189. This half revolution of eccentric 192 raises shift frame 205 to its lower case position. As shift frame 205 is thus raised and restored, the switch lever 347 thereon is also raised relatively to stud 348 and freed for counterclockwise movement, thereby letting switch blade b move resiliently to break contact with blade c and remake its contact with blade a. In the raising or restoration of shift frame 205, the lever 330 turns counterclockwise, about rod 334 as a fulcrum, to normal position, Fig. 6.

When a case shift is effected ordinarily, that is, in response to manual operation of case shift key lever 183, the lever 206 and parts, including stop 327, controlled thereby remain in normal positions. Under this condition, the case shift movements of shift frame 205 and its stud extension 203a, which carries lever 330, turn said lever idly about rod 334, since said lever may bear idly against said rod 334 as a fulcrum under the urge of spring 332. The stop 327, being in normal position, does not arrest the movement of lever 330, and, hence, the latter does not operate upon lever 337 for disconnecting the "9" type bar 24 at ordinary shift to upper case.

Circuits and their operation

The escapement switch 265 is preferably connected in one of the leads 361, Fig. 10, to the input side of a transformer S connectible by a plug 368 to an A. C. current supply. The output of the transformer goes to a current rectifier 369 to which are connected a common lead 370 to one terminal of each of the magnets M, SH, and a lead 147a to the common contact strip 147 for the upper contact blades 141. Each of the ten type action magnets M has its other terminal connected by a lead 371 to the corresponding lower contact blade 139. The lead 371 for the "9" magnet M has a lead 372 to the contact blade c, shown also in Figs. 4, 6. One terminal of the case shift magnet SH is connected to the common lead 370, and its other terminal is connected by a lead 373 to the contact blade a with which the middle contact blade b is normally in contact. The middle contact blade b has a lead 374 to that lower contact blade 139 which is operable by the cross blade 135, Fig. 1, under control of the carriage and highest unit 71 when the latter registers an overdraft "9." When blade 135 is lifted and closes its normally separated contact blades 139, 141, the case shift magnet SH takes a current through the following circuit: rectifier 369, lead 370, magnet SH, lead 373, closed contact blades a and b, lead 374, closed contact blades 139, 141, common contact strip 147, and lead 147a back to rectifier 369.

The resulting case shift operation moves the middle contact blade b to the dotted line position, Fig. 10, to open the contact blades a and b to cut out magnet SH and, instead, close the con-

tact blades *b* and *c* to direct current to the "9" magnet *M* through the following circuit: rectifier 369, lead 370, "9" magnet *M*, leads 371, 372, closed contact blades *c*, *b*, lead 374, closed contacts 139, 141, common contact strip 147, and lead 147^a back to rectifier 369. The case shift which has already occurred has caused the disconnection of the "9" type bar, by disconnecting the "9" sub-lever parts 338, 342, so that the operation of the lower sub-lever part 342, without printing, which results from exciting the "9" magnet by way of the closed contact blades 139, 141, and *b*, *c*, indexes "9" in the highest pin bar 72 and operates the escapement dog rocker 230 counterclockwise from the Fig. 8 to the Fig. 9 position by way of shaft 315 and its connections to the frame 243, 245, Fig. 4. The resulting release and swing of the stepping dog 233 from the Fig. 8 to the Fig. 9 position has caused the escapement switch 265 to open the primary side of the transformer. This deenergizes the "9" magnet *M*, and, further, this "9" magnet *M*, or any other magnet, cannot be energized again until switch 265 is reclosed by the letter feed step of the carriage swinging stepping dog 233 back to the Fig. 8 position. This letter feed step results as the dog rocker 230 swings clockwise back to the Fig. 8 position and thereby releases the carriage from the holding dog 232 and interposes the stepping dog 233 in the path of the next escapement wheel tooth.

At the lift of any other of the computing base cross blades 134 under control of the computing pinion and the carriage, to close its contact blades 139, 141, the corresponding magnet *M* takes current. The circuits and operation for the several magnets *M* are similar, and, therefore, there will be described only the following circuit and operation for, say, the "1" magnet *M*: rectifier 369, lead 370, "1" magnet *M*, lead 371, closed contact blades 139, 141, common contact strip 147, and lead 147^a back to rectifier 369. The resulting energization of the "1" magnet *M* causes the "1" type action to be operated in a printing stroke, toward the end of which the 1 type bar operates universal bar 259 to rock dog rocker 230 counterclockwise from the Fig. 8 to the Fig. 9 position preparatory to a letter feed step of the carriage. The attendant clockwise rocking of stepping dog 233 about pivot 234 to the Fig. 9 position causes the switch 265 to be opened. This deenergizes the "1" magnet *M*, and this magnet, or any other magnet, cannot be energized again until switch 265 is reclosed by the stepping dog 233 being moved back to the Fig. 8 position by the carriage taking its letter feed step upon return of the dog rocker 230 as the operated "1" type bar recoils from the platen.

It will be evident now that as far as operation of any type action is concerned the switch 265 is opened before the carriage starts a letter feed step and is reclosed only at about the instant the carriage completes the step and that there is practically little or no possibility of operating another magnet and, hence, starting another type action operation while the carriage is taking its letter feed step. This provides for timing the incidences of type action operations sufficiently apart to avoid clashing of type bars; moreover, a type action and its pin-setting bar 78 will not be operated while a pin bar 72 is being restored from, and the next pin bar 72 is being advanced to, pin-setting position during the letter feed step of the carriage, and, so, collision between a pin-setting bar 78 and a pin bar 72 is avoided, reliable indexing is assured, and, further, the serial

operations of the type actions proceed at an even or regular tempo or beat.

Variations may be resorted to within the scope of the invention, and portions of the improvements may be used without others.

What is claimed is:

1. In a machine of the character described, having a totalizer, the combination with a plurality of numeral type actions and means to operate 10 said type actions automatically, one by one, according to a total in said totalizer, one of said type actions including an insignificant-figure-typing member and an operating member and also including an operable coupler normally coupling said members, of total-taking-control means, an element moving to an operated position in response to operation of said control means preparatory to printing a total, a disjointable connection between said element and coupler normally effective to operate said coupler so as to have the typing member disconnected from the operating member when said element is in operated position, said connection being disjointable to release the operated coupler for reconnecting said type action members, and means operable by another type action to disjoint said connection, while said element remains in operated position, to release the coupler.

2. In a machine of the character described, 30 having a totalizer, the combination with a plurality of numeral type actions and means to operate said type actions automatically, one by one, according to a total in said totalizer, one of said type actions including an insignificant-figure-typing member and an operating member and also including an operable coupler normally coupling said members, of total-taking-control means, an element moving to an operated position in response to operating said control means 35 preparatory to printing a total, a disjointable connection between said element and coupler normally effective to operate said coupler so as to have the typing member disconnected from the operating member when said element is in operated position, said connection being disjointable to release the operated coupler for reconnecting said type action members, means operable by another type action to disjoint said connection, while said element remains in operated position, 40 to release the coupler, means subsequently operable to restore said element and means effective to restore said disjointed connection upon restoration of said element.

3. In a machine of the character described, 55 having a totalizer, the combination with a plurality of numeral type actions and means to operate said type actions automatically, one by one, according to a total in said totalizer, one of said type actions including an insignificant-figure-typing member and an operating member and also including an operable coupler normally coupling said members, of total-taking-control means, an element moving to an operated position 60 in response to operation of said control means preparatory to printing a total, a disjointable connection between said element and coupler normally effective to operate said coupler so as to have the typing member disconnected from the operating member when said element is in operated position, said connection being disjointable to release the operated coupler for reconnecting said type action members, a case-shiftable part, and means operable by a case shift of said part 65 to disjoint said connection, while said control

element remains in operated position, to release the coupler.

4. In a machine of the character described, having a totalizer, the combination with a plurality of numeral type actions and means to operate said type actions automatically, one by one, according to a total in said totalizer, one of said type actions including an insignificant-figure-typing member and an operating member and also including an operable coupler normally coupling said members, of total-taking-control means, an element moving to an operated position in response to operation of said control means preparatory to printing a total, a disjointable connection between said element and coupler normally effective to operate said coupler so as to have the typing member disconnected from the operating member when said element is in operated position, said connection being disjointable to release the operated coupler for reconnecting said type action members, a case-shiftable part, and means including devices effective upon operating another type action or upon case shifting said part to disjoint said connection, while said control element remains in operated position, to release said coupler.

5. In a combined typewriting and computing machine having a typing carriage and a totalizer, the combination with numeral type actions and mechanism, including an element initially movable to an operated position, for effecting automatic operation of said type actions under control of said totalizer and carriage to print a total, two of said type actions including each an operating member, a typing member, and an operable coupler normally connecting said members, of a disjointable connection operable by the initial movement of said element to operate the coupler of one of said two type actions to disconnect its members, a case shift mechanism operable under control of the totalizer and carriage, and means coacting with operation of the case shift mechanism to operate the coupler of the other of said two type actions to disconnect its members and to disjoint said connection to free the first-operated coupler and thereby permit it to reconnect the first-disconnected type action members.

6. In a combined typewriting and computing machine having a totalizer and a carriage, the combination of type actions each comprising a typing member and an operating member normally operatively connected, the members of one of said type actions having an operable coupler urged to coupling condition, a universal bar operable by said typing members, a case-shiftable part, a settable control for said coupler, mechanism operative under control of said totalizer and carriage to set said control and then to case shift said part, means, governed by the set control, to coact with the case shift of said part to operate said coupler to disconnect said members of said one type action, and means operatively connecting said control to said universal bar at the case shift of said part so that said control becomes disabled, upon operation of said universal bar by another type action, for resulting restoration of said coupler.

7. In a machine of the character described, the combination with a totalizer, of typing mechanism, including a type-action having a sub-lever composed of a driving member and a driven type-actuating member, a common fulcrum axis on which said members are pivoted side by side, a coupling lever fulcrumed on one of said mem-

bers and normally having a position in which it has coupling connection with the other member, a total-taking control, including a rockable member, operable preparatory to operating said typing mechanism to type a total in the totalizer, and lever mechanism operatively connecting the rockable member of said control and said coupling lever and effective upon operating said control, to move said coupling lever to position to disconnect said sub-lever driving and driven members.

8. In a machine of the character described, the combination with a totalizer, and a type-action having a driving member, type-actuating driven member and a device normally coupling said members and operable to uncouple said members, of a case-shiftable part, a two-armed lever carried by said part, a rest forming a fulcrum engaged by one arm of said lever and about which said lever is constrained to turn in one direction when said part is case shifted from a normal position, a stop interposable to arrest another arm of said lever and cause it to turn in the opposite direction at said shift of said part, means operatively connecting said lever and said coupling device so that the latter is operated to uncouple said members at the shift of said part if said stop has been interposed, and means operable under control of said totalizer to interpose said stop.

9. In a machine of the character described, having a power-operated driver, a type-action actuator movable into position for actuation by the driver, and amount-indexing mechanism; a numeral type action cooperative with the indexing mechanism to index its numerical value and conditionable for non-printing or for printing its numerical concomitantly with indexing, said type action comprising a type bar, a sub-lever including a driving member and a driven member, said driven member being operatively connected to the type bar, said driving member having two arms rigid therewith, one arm directly connected to said actuator, the other arm having a connection to actuate said indexing mechanism, a common fulcrum axis on which said members are pivoted side by side, each of said members having an opening in substantial registry, and a coupler movable on one of said members and having a part seatable in said openings for joint actuation of the type bar and indexing mechanism, and withdrawable therefrom for actuation of the indexing mechanism alone.

10. In a combined typewriting and computing machine having a totalizer which may contain the complement of a true negative total, and a typing carriage, the combination with a case shift mechanism, and an operable numeral-value device, of two magnets individually excitable for determining operation of said case shift mechanism and said device, respectively, means, operable under control of said totalizer containing a complementary negative total, the unoperated case shift mechanism and carriage, to excite the case shift magnet for resulting operation of the case shift mechanism, and means, operable under control of said totalizer, the carriage and the operated case shift mechanism, to excite the other magnet for resulting operation of said numeral value device.

11. In a machine of the character described adapted to type totals and having a carriage movable in denominational order steps through a total-typing zone, the combination of a totalizer operable to an overdraft condition, a case-

shiftable part, a power drive, a case shift control shiftable to and from an operated position, a clutch device operatively connected to said control so as to be effective upon the shifts of said control to and from operated position to enable said power drive respectively to case shift and restore said part before and after typing an overdraft, an actuator for said control connectable to said power drive, and means operable partly under control of said totalizer at overdraft and partly under control of said carriage at said zone to connect said actuator to said power drive for resulting shift of said control and case shift of said part.

12. In a machine of the character described adapted to type totals and having a carriage movable in denominational order steps through a total-typing zone, the combination of a totalizer operable to an overdraft condition, a case-shiftable part, a power drive, a case shift control shiftable to and from an operated position, a clutch device operatively connected to said control so as to be effective upon the shifts of said control to and from operated position to enable said power drive respectively to case shift and restore said part before and after typing an overdraft, an actuator for said control connectable to said power drive, means operable partly under control of said totalizer at overdraft and partly under control of said carriage at said zone to connect said actuator to said power drive for resulting shift of said control and case shift of said

part, said control tending to return from operated position, and means to keep releasably said actuator and, hence, said control in operated position.

13. In a machine of the character described adapted to type totals and having a carriage movable in denominational order steps through a total-typing zone, the combination of a totalizer operable to an overdraft condition, a case-shiftable part, a power drive, a case shift control shiftable to and from an operated position, a clutch device operatively connected to said control so as to be effective upon the shifts of said control to and from operated position to enable said power drive respectively to case shift and restore said part before and after typing an overdraft, an actuator for said control connectable to said power drive, means operable partly under control of said totalizer at overdraft and partly under control of said carriage at said zone to connect said actuator to said power drive for resulting shift of said control and case shift of said part, said control tending to return from operated position, means to keep releasably said actuator and, hence, said control in operated position, a general operator mechanism, and means cooperative therewith to release said actuator from said keeping means for resulting return of said control and case shift of said part back to normal.

HENRY L. PITMAN.
